UNITED STATES PATENT OFFICE

2,000,589

EXPOSURE CONTROL APPARATUS

Albert B. Fuller, Rochester, N. Y., assignor to
 Eastman Kodak Company, Rochester, N. Y., a
 corporation of New York

Application August 10, 1931, Serial No. 556,199

3 Claims. (CL 250—41.5)

My invention relates to automatic light timing devices particularly adapted for use in photographic printing where a range of unvarying exposures is required.

5 One object of my invention is to provide a practical and reliable control circuit which will automatically vary the period of exposure in accordance with variations in the intensity of the light source due to any cause in such a way 10 as to give a definite ultimate amount of light for a given exposure.

Another object of my invention is to provide exposure controlling mechanisms which will selectively give different required exposures.

15 Another object is to provide a control circuit having a plurality of settings which may be used one at a time. Another object is to provide an exposure controlling mechanism having variable light integrating means for automatically obtaining a range of predetermined exposures.

20 Other objects will appear from the following description and the novel features will be pointed out in the appended claims.

Figure 1 of the accompanying drawing shows 25 a circuit organization whereby my invention may be carried into effect and Figure 2 shows a modified light integrating system.

A light source 1 adapted to be energized from a source of power 2 through a switch 3 furnishes 30 light to a printing plane 4 for exposing a sensitive emulsion in any well known manner. A photo-electric element 5 positioned to be illuminated by the source 1 is connected in shunt relation with a condenser 6.

35 The condenser 6 is adapted to be charged by a battery 7 through a contact 8 and to be discharged through the photo-electric element 5. The capacity in circuit with the cell 5 may be selectively varied by switching in one or more 40 of the condensers 9, 10, and 11. The switch 3 is normally open and may be closed by momentarily closing a hand operated contact 12 which connects the coil 13 of the switch 3 through a normally closed contact 14 to the source of 45 power 2 at the same time opening switch 8. A critical relay 15 of the gaseous discharge type having its grid and anode connected to the condenser 6 and its anode and cathode connected to the source 2 through the operating coil 16 50 of the contact 14 controls the opening of the switch 3.

In the operation of the device the capacity in circuit with the condenser 6 is set at a value which is known to give the desired exposure at 55 the plane 4. The switch 3 being open the con-

tact 8 is closed and the condenser is charged to the potential of the battery 7. The contact 12 is momentarily closed which energizes the coil 13 and closes the switch 3. The closing of the switch 3 completes the circuit of the coil 13 which holds the switch 3 closed until the circuit is opened by the contact 14. The closing of the switch 3 also energizes the light source 1 to start the exposure and opens the contact 8 in the battery circuit. The condenser 6 now discharges through the element 5, the conductivity of which corresponds to the intensity of the light received from the source 1. The potential of the grid of the relay 15 decreases with the potential of the condenser as it discharges, and 10 when the potential reaches the critical value, a current passes between the anode and the cathode which energizes the coil 16 and opens the contact 14. 15

The opening of the contact 14 breaks the circuit through the coil 13 and permits the switch 3 to open to discontinue the exposure and to remove the anode voltage for stopping the current flow through the relay 15.

In Figure 2 I have shown a modified form of 25 circuit for the condenser 6. In this figure the circuit is so arranged that the charging of the condenser 6' through the photo-electric cell 5 is utilized to integrate the light received from the source 1. The push button 12 controls the 30 closing of the switch 3 to energize the light source 1 and the critical relay 15 controls the opening of the switch 3 as in Figure 1.

In the operation of the system as shown in 35 Figure 2 when the switch 3 closes to energize the light source, the contact 8 completes the circuit of the battery 7 through the element 5 and the condenser 6'. The rate at which the potential on the condenser 6' increases depends upon the conductance of the element 5 and 40 when this potential reaches the critical value a current flows through the relay 16 and opens the contact 14 which permits the switch 3 to open as in Figure 1.

In Figure 2 the condenser 6' is illustrated as 45 a variable condenser with definite settings of capacity indicated at A, B, C, D and E, and for each setting the system will automatically give a certain definite exposure in the same manner as the various capacities of the condenser 6 in Figure 1. It is obvious that the variable condenser of Figure 2 may be used in the circuit of Figure 1 and that the condensers of Figure 1 may be used in the circuit of Figure 2.

The use of the discharge of a condenser 55

through a photoconductive element to integrate light is described in detail in United States application Serial No. 536,061, filed May 8, 1931, by Armand Georges Denis.

5 I may use any well known type of critical relay and probably the simplest would be a grid glow tube which operates as readily with A. C. as with D. C. Any other type may be used as for example an ordinary vacuum tube with a
10 dynamic relay.

10 While I have shown the exposure as being controlled by switching on and off the source of light, obviously a shutter arrangement may be operated by the coil 13 to control the exposure. Various other modifications and equivalents of my invention will readily suggest themselves to persons skilled in the art without departing from the scope of my invention as set forth in the appended claims.

15 20 What I claim as new and desire to secure by Letters Patent of the United States is:

1. The combination with an electric circuit, a photographic lamp in said circuit, a switch for making and breaking said circuit, a light sensitive element the conductivity of which varies with the intensity of said lamp, a capacity in series with a battery and said element, means
25

for closing the battery circuit when said lamp is energized and means controlled by the charge on said capacity for opening the lamp circuit, said capacity being selectively variable.

2. A control circuit for a photographic lamp including a switch for making and breaking the lamp circuit, a photo-sensitive element positioned to be illuminated by said lamp, a condenser and a battery, means for simultaneously making said circuit and for connecting said element and said condenser in series relation with said battery whereby said condenser is charged through said element and means for breaking said circuit when said condenser has charged to a pre-determined potential. 5
10

3. An exposure controlling mechanism adapted to selectively give a variety of pre-determined exposures including electric storage means of adjustable capacity and a photo-sensitive element, an electric lamp, a switch for closing a circuit to said lamp, means for charging said storage means through said element and means for opening the circuit of said lamp in response to a predetermined charge on said condenser, the conductance of said element being determined by the intensity of said lamp. 20
